UNITED STATES PATENT OFFICE.

FREDERICK ACKERMAN AND JAMES H. SULLIVAN, OF VANCOUVER, BRITISH COLUMBIA, CANADA.

MUSIC-LEAF TURNER.

1,112,400.

Specification of Letters Patent. Patented Sept. 29, 1914.

Application filed April 2, 1914. Serial No. 829,100.

To all whom it may concern:

Be it known that we, FREDERICK ACKERMAN, a subject of the Emperor of Germany, and JAMES H. SULLIVAN, a citizen of the 5 United States, both residents of the city of Vancouver, in the Province of British Columbia, Canada, have invented certain new and useful Improvements in Music-Leaf Turners, of which the following is a specification.

Our invention relates to improvements in music leaf turners of the class shown in the application for United States Patent, prepared and executed by us on the 13th day of 15 February, 1914, which application was filed on the 6th day of March, 1914, under Serial No. 822,876, the apparatus therein shown comprising a series of tubular members rotatably disposed within each other, and suitably supported on a base, leaf engaging arms carried by each of the tubular members, mechanism for successively rotating the tubular members, and a lever for actuating the mechanism.

25 Our present invention consists in the improved construction of the mechanism for rotating the tubular members and of the lever for operating the said mechanism, and the object of our invention is to devise a 30 means whereby the leaf engaging arms are actuated automatically and in a much quicker manner than is possible in the device as shown in the application referred to, in which the said arms are described as actuated by a lever moved by the hand of the 35 player during the complete travel of the leaf engaging arm from right to left, whereas in our present device the movement of the arms is automatic, a quick and slight 40 touch of the hand on the lever being all that is necessary to actuate the mechanism to rotate the arms.

We attain this object by the means illustrated in the accompanying drawings in 45 which—

Figure 1 is a side elevation of the lower portion of our device, showing the mechanism. Fig. 2 is a plan view of the mechanism. Fig. 3 is a plan view of the improved 50 lever and operating gear.

Similar figures of reference indicate similar parts throughout the several views.

1 is the base of our device, formed of any suitable material and of suitable dimensions.

2 is a wall of the same material as the base 1, which extends around the base on the upper face thereof, being secured firmly thereto and having the threaded holes 3 provided therethrough by means of which holes and 60 suitable screws therefor the cover 4, which cover is shown in Figs. 1 and 2 of the application referred to, is detachably connected to the base 1 to inclose the operating mechanism of the device. 65

9 is a plate carried by the base 1 and supported at a suitable height therefrom by means of the corner posts 10, the lower ends of which posts are rigidly secured into the base while their upper ends are adapted to 70 receive the screws 11, which screws secure the plate 9 to the posts 10.

The operating rods are, in the device taken for illustration, four in number, 11, 12, 13, and 14, and are formed of hollow 75 tubing, with the exception of 14, which may be either hollow or solid. These rods work within each other, as shown more particularly in Figs. 3 and 5 of the application referred to, that is to say, 11 is the outer rod, 80 through which pass all the rest in the order named, viz., 12 through 11, 13 through 12, and 14 through 13. The operating rods, when assembled together, pass through an opening in the plate 9 and are rotatably 85 supported by the inner rod 14, the lower end of which passes through the base and is shouldered thereon.

15 are pinions secured on the lower ends of the operating rods. 90

22 is a cylinder adapted to be rotatable between the plate 9 and the upper face of the base 1, on the periphery of which cylinder are provided, at specified positions, sets of teeth 23 which are adapted to engage successively the pinions 15 as the cylinder is rotated. The number and pitch of the teeth 23, it may be here stated, and also of the teeth of the pinions 15, is such that one complete travel of each set of teeth 23 will cause 100 the respective rod which is actuated thereby through its respective pinion to revolve one-half turn in either direction, according to the rotation of the cylinder 22. The cylinder 22 is rotated by means of the pinion 105 24, which is secured to the lower end of the cylinder, and the gear 25, which engages the pinion 24.

So far the device is as shown in the application referred to, except as regards the 110

operating of the rods and the gear 25. In that application there is a lever 26 secured into the gear 25 by means of which lever the gear 25 is actuated to rotate the cylinder 22, which in turn actuates successively the pinions 15 and thus operates the rods 11, 12, 13, and 14. This construction, while quite efficient as far as the operation of the rods is concerned, requires that the player must 10 press the lever 26 around from right to left, keeping the hand on it during the complete movement required to turn a leaf. Speed of turning the leaves, however, is an important factor in such a device, and it is found the 15 leaves are turned much quicker by our improved construction, now to be explained, than they are by the construction disclosed in the application hereinbefore mentioned.

Referring now to the drawings, 27 is a 20 normally wound-up spring such as a watch spring or its equivalent, secured to the spindle of the cylinder 22 and the plate 9, and adapted to rotate the cylinder when unwinding.

25 28 are stops suitably positioned on the periphery of the cylinder 22.

29 is a pawl carried on the underside of the plate 9, being fulcrumed thereon by means of the pin 30 and against which pawl 30 the stops 28 are adapted to engage successively as the cylinder 22 rotates. The outer end 31 of the pawl 29 is downwardly turned and extended so as to be normally engaged against the edge of the lever 32. The lever 35 32 is hingedly connected to the gear 25, preferably as shown in Fig. 3.

33 is a plate spring, secured to the gear 25 and adapted to bear against the underside of the lever 32 so that the lever, instead of 40 lying flat, will lie in a normally inclined position, as shown in Fig. 1, in which position it bears against the downwardly turned end 31 of the pawl 29.

34 is a spring adapted to bear against the 45 pawl 29, as shown in Fig. 2, to return same to its normal position after having been moved by the lever 32.

It will now be seen that when our device is ready for use, it being understood that the 50 spring 27 is then wound-up, the unwinding of the spring 27 and consequent rotation of the cylinder 22 is prevented by the engagement of any one of the stops 28 with the pawl 29. Therefore, in order to operate our 55 device, all that is necessary is simply to touch the outer end of the lever 32 quickly to depress same, whereupon the downwardly turned end 31 of the pawl 29 is forced away from the lever 32, thus swinging the pawl 60 on the pin 30 and disengaging it from the stop 28 with which it was then engaged.

The tension on the spring 27 being thus relieved, the cylinder 22 will rotate quickly, causing the operating rod and leaf engaging arm to be actuated as hereinbefore described. 65 The downward pressure on the lever 32 being meanwhile relieved, the spring 33 brings the lever 32 back to its normal inclined position, and the spring 34 brings the pawl into its normal position so that it may engage 70 the succeeding stop 28 and keep the cylinder from rotating until it is necessary to turn another leaf, the foregoing action being then repeated, and successively until all the leaves have turned, when a simple continuous 75 movement of the lever 32 from left to right brings all the leaves back to the commencing position and at the same time re-winds the spring 27 again. It will, of course, be understood, that the stops 28 are so positioned 80 that the distances therebetween allow for the complete turning movement of each of the leaf engaging arms from right to left at each successive release of the cylinder 22.

What we claim as our invention is:

1. In a music leaf turner, a plurality of turnable members having partial rotary movement about a common axis, driving mechanism for the turnable members, a spring normally in tension for operating 90 said driving mechanism, means for locking the spring in tension, a lever for re-winding the spring and means operated by said re-winding lever for releasing said locking means whereby the spring turns the turnable members individually a predetermined distance.

2. In a music leaf turner, the combination, with vertically supported revoluble tubular members, of pinions carried by the 100 said tubular members, a normally wound-up spring, a revoluble toothed cylinder operated by the unwinding of said spring and adapted to successively rotate the said pinions, stops on the said cylinder, a suitably 105 mounted pawl adapted to normally engage the said stops so as to limit each successive movement of the cylinder, a pinion carried by the cylinder, a gear engaging said pinion, a lever hingedly connected to the said 110 gear, said lever being adapted to throw the pawl out of engagement with said stops to free the cylinder and means for returning the pawl to its normal position, as and for the purpose specified.

Dated at Vancouver, B. C., this tenth day of March, A. D. 1914.

FRED ACKERMAN.
JAMES H. SULLIVAN.
